VARIABLE-SPEED PHONOGRAPH
TURNTABLEEdward A. HermSEN, Honolulu, Territory of
Hawaii

Application July 2, 1949, Serial No. 102,860

10 Claims. (Cl. 274—9)

1

This invention relates to new and useful improvements in variable speed phonograph turntables.

Hitherto, standard phonographs have been equipped with turntables revolving at 78 R. P. M. Recently, manufacturers of phonograph records have offered for sale records for use in machines rotating at 45 R. P. M. or 33½ R. P. M. Such records will not produce intelligible sounds if rotated at 78 R. P. M.

Accordingly, the principal object of the present invention is to provide a device which may be installed on conventional 78 R. P. M. turntables and which will by suitable speed reduction means, cause records to rotate at either 45 R. P. M. or 33½ R. P. M. The invention may also be used to rotate records at approximately 25 R. P. M., if it should be desired to operate at that speed. Furthermore, the invention may easily be converted to change the speed of turntables operating at either 33½ R. P. M. or 45 R. P. M. to rotate records at 78 R. P. M., or, in other words, the device may be used to convert slowly rotating turntables to a higher speed.

A principal feature of the present invention is that it may be easily installed on a standard phonograph without complicated attachments or installation service and may be instantly removed if desired.

The attachment may be left on the phonograph when 78 R. P. M. records are being played and may be rapidly adjusted for either 45 R. P. M. or 33½ R. P. M. records without the use of any tools.

Other features of the present invention are the neat appearance and light weight of the device, its strength and dependability.

Still another feature is the fact that the device is small and occupies very little space on the phonograph turntable.

Further objects of the present invention will become apparent upon reading the following specification and referring to the accompanying drawings in which similar characters of reference represent corresponding parts in each of the several views.

Fig. 1 is a vertical section through the device.

Fig. 2 is a section taken substantially along the line 2—2 of Fig. 1.

Fig. 3 is a section taken substantially along the line 3—3 of Fig. 1.

Fig. 4 is an enlarged view of a portion of the rim of the device.

Fig. 5 is a fragmentary section taken substantially along the line 5—5 of Fig. 4.

Fig. 6 is a fragmentary section taken substan-

2

tially along the line 6—6 of Fig. 4 with stop arm retracted.

Fig. 7 is a fragmentary section taken substantially along the line 7—7 of Fig. 4.

Fig. 8 is a fragmentary section taken substantially along the line 8—8 of Fig. 4.

Fig. 9 is a side elevation drawn to reduced scale showing use of a spool fitting over the conventional spindle in order to center a record having a large diameter center hole.

Fig. 10 is an enlarged view of a portion of the rim of a modification of the invention.

In Fig. 1 there is shown a conventional rotatable phonograph turntable 15 spaced from and revolving above a platform 16. Said turntable is rotated by a motor at a speed of 78 R. P. M. Projecting upwardly from the surface of the turntable is a spindle 17 having a diameter slightly less than the diameter of the central hole 18 commonly formed in conventional phonograph disc record 19. The present invention is designed to fit over the spindle 17 and rest upon the turntable 15.

The device is constructed about a central hub 21 having a central bore 22 flared outwardly at either end thereof and having a minimum diameter slightly greater than the diameter of the spindle 17. Thus, the hub 21 is centered about the axis of the spindle 17, is easily inserted thereupon and has a minimum of frictional engagement therewith. The flaring of the central bore 22 also facilitates installation when a bent or off-set spindle such as used in many automatic record changing machines is incorporated in the phonograph. The exterior of hub 21 is threaded and at the upper end thereof is a projecting circumferential shoulder 23 constituting an abutment.

The hub 21 receives three circular, horizontally disposed plates 24, 25 and 26. The outermost plates 24 and 26 are spaced from the innermost plate 25 by graphite washers 28 so that there is a minimum of frictional resistance to rotation of any of the plates with respect to the others.

The upper plate 26 abuts shoulder 23 and a nut 29 is threaded upon the hub 21 and bears against the lowermost plate 24. A lock nut 31 is also threaded over the hub. The three plates 24, 25 and 26 are thus held centrally disposed about the axis of spindle 17 but do not necessarily rotate at the same speed as said spindle. The outer portions of the plates are disposed substantially parallel but are formed so that the space between upper plate 26 and center plate 55 25 is greater than the distance between center

plate 25 and lower plate 24 so as properly to accommodate the speed reduction gears herein-after mentioned. The lower surface of lower plate 24 is provided with a layer of felt 32 which engages turntable 15 and causes the lower plate 24 at all times to rotate with and at the same speed as the turntable. The upper surface of upper plate 26 is likewise provided with a layer of felt 33 and the disc record 19 is placed on such felt so that the record 19 at all times rotates with and at the same speed as upper plate 26.

Two annular rings 35 and 36 of substantially the same diameter are disposed between the plates. The upper ring 36 is provided with a groove 37 in its upper surface and the downwardly turned periphery 38 of upper plate 26 fits within said groove and cooperates in holding the ring 36 centrally disposed. Similarly, the lower ring 35 is provided with a circular groove 39 in its lower face which receives the upwardly turned periphery 41 of lower plate 24. Central plate 25 fits partially between the two rings 35 and 36 and for such purpose the upper ring 36 is provided with an annular depression 42 in its lower face and the lower ring 35 is provided with a similar depression 43 in its upper face. Spaced about the rings 35 and 36 are chordal slots 44. Rollers 46 positioned within the slots 44 and screws 47 extending radially of said rings and extending through holes in the axes of said rollers provide mountings for said rollers. The rollers 46 in the upper ring 36 engage the under surface of upper plate 26 and the upper surface of central plate 25 and the rollers 46 in the lower ring 35 engage the under surface of central plate 25 and the upper surface of lower plate 24. Thus, the rollers 46 perform two functions, namely, they cooperate with the graphite washers 28 to space apart and hold in parallel alignment the plates 24, 25 and 26, and, further, they provide for free rotation of the ring 35 and 36 with respect to said plates. The inner cylindrical edges of each of rings 35 and 36 are provided with gear teeth and thus constitute circular racks 48 and 49. The rack 48 of lower ring 35 meshes with a plurality of spaced planetary gears 51 which are mounted upon central plate 25 by shafts 51a. Said gears 51 also mesh with ring gear 52 mounted upon lower plate 24. There are preferably at least three such gears 51, and hence the ring 35 is held centrally disposed by said gears and flanges 41 in grooves 39.

As will hereinabove appear, means are provided for holding the lower ring 35 stationary at the selection of the operator. Thus, rotation of the turntable 15 causes rotation of lower plate 24 and with it, ring gear 52. Since planetary gears 51 mesh both with ring gear 52 and circular rack 48, and since the circular rack 48 is held stationary this causes central plate 25 to revolve, but at a different speed than lower plate 24.

As will also further appear, means is provided for causing central plate 25 and upper plate 26 to revolve at the same speed when ring 35 is held stationary. Thus, it is possible by proper gear ratios to convert rotation of turntable 15 at 78 R. P. M. to rotation of disc record 19 at 33½ R. P. M.

In the event that the disc record is of the type which is to be rotated at 45 R. P. M., a different gear ratio is required, and this is provided by holding upper ring 36 stationary (by means herein-after described) and causing lower plate 24 and central plate 25 to rotate together (also by means herein-after described). For this purpose the ring 36 is formed with a circular rack 49 on its in-

terior surface and a ring gear 53 is fixed to central plate 25. A plurality of composite planetary gears 54 is mounted for rotation on upper plate 26 by shafts 54a. The lower part 56 of composite gear 54 meshes with ring gear 53 and the upper part 57 of composite gear 54 meshes with circular rack 49. Proper selection of gear ratios for the ring gear 53, circular rack 49, upper portion 57 and lower portion 56, cause the upper plate 26, and hence record 19 to rotate at a speed of 45 R. P. M. when the central plate 25 rotates at 78 R. P. M.

Each of the rings 35 and 36 is provided with means selectively operable for holding the rings stationary, as has been mentioned. Since the means for each ring is substantially the same, only the means for upper ring 36 will be described, it being understood that ring 35 is provided with similar mechanism. A segment 61 is cut out of a portion of the upper outer edge of upper ring 36. Fitting within this cut out segment is a stop arm 62 pivotally connected adjacent one of its ends to said ring by pivot 63. Said stop arm is biased outwardly by a leaf spring 64 fixed at one end to arm 62 and bearing at its other end against ring 36. Bracket 66 holds the pivot for roller 46 where segment 61 is cut out of ring 36. Outward movement of said stop arm is adjustably limited by a block 67 adjustably positioned in an arcuate groove 68 in the surface of said ring which communicates with the cut out portion 61. The block 67 and inner end of stop arm 62 are arranged to abut one another and hence pivotal movement of the stop arm 62 is restrained when the surface 69 of inner end of the stop arm abuts surface 71 of block 67. Adjustment of position of block 67 thus adjusts the outward movement of stop arm about pivot point 63. Adjustability is provided by adjustment of the position of screw 72 threaded into ring 36 in arcuate slot 73 in block 67. A stationary stud 74 is fixed to platform 16 and positioned outwardly from spindle 17 so that the surface 76 of the stop arm engages said stud 74 and thus rotation of ring 36 is prevented. A latch element 77 is cut into the underside of the outer end of stop arm 62 and this latch element engages latch 78 attached to ring 36. The latch 78 is carried by one end of upwardly-biased spring 79 attached at its other end to ring 36, the spring being disposed in chordal slot 81 formed within the ring 36.

A finger catch 82 attached to the middle of spring 79 projects upwardly through a hole in ring 36 and is conveniently accessible to the operator of the machine. When the operator depresses the finger catch 82, such action forces the latch 78 downwardly and disengages it from the cooperating latch member 77 on stop arm 62 which moves outwardly under action of spring 64. When it is desired to return the stop arm 62 to inward position, the operator moves the arm against the action of spring 64 and the latch 78 biased upwardly by spring 79 engages the corresponding latch element 77 and holds the stop arm 62 in inward position.

The stop arm 62 carries an inwardly projecting extension 83 which, when the stop arm is in inward position, projects into an inwardly directed groove extension 84 of the cut out portion 61 as best indicated in Fig. 6. The positioning of said extension 83 within the groove 84 forces apart a pair of horizontally extending leaf springs 86 which are normally biased to fit inside the groove extension 84. Said springs 86 are engaged by extension 83 substantially at their midpoints. One end of each of said springs 86 is fixed to the

ring 36 and the other end of each spring bears a projecting stud 87 (see Fig. 8). Spaced circumferentially about a circle inwardly disposed of the periphery of each of plates 25 and 26 is a series of holes 88 slightly larger than studs 87. The studs 87 may fit within any of said holes when forced out of the groove extension 84 by inward movement of extension 83 of stop arm 62. The studs 87 thus fit within the closest hole 88 and such action locks the ring 36 which carries the studs 87 to the adjacent plates 25 and 26 so that the plate 25, ring 36 and plate 26 all rotate together.

When the stop arm 62 is projected outwardly by depressing catch 82 the springs 86 pull the studs 87 inwardly and thus disengage said studs from the holes 88 and permit relative movement of the plate 25, ring 36 and plate 26. Since outward projection of the stop arm 62 holds ring 36 stationary, the plate 25 and plate 26 thereupon rotate at different speeds dependent upon the gear ratio of the ring gear 53, circular rack 49 and planetary gears 54.

It will be understood that the ring 35 also bears a corresponding stop arm 62 and corresponding studs 87 which fit within holes 88 spaced circumferentially about the plates 24 and 25 and that the operator may cause the lower stop arm 62 to project outwardly by pressing lower finger catch 82 and thus hold the ring 35 stationary and permit relative rotation of the plate 24 with respect to the plate 25. When the lower stop arm 62 is positioned inwardly, the studs 87 project into holes 88 in plates 24 and 25 and cause the plate 24, ring 35 and plate 25 to rotate together.

Inasmuch as certain "slow speed" records have center holes larger than those of conventional records, a spool 91 having a hole in its axis of a diameter equal to that of spindle 17 and having an outer diameter equal to that of the enlarged center holes of such records may be installed to fit over the spindle 17. The spool 91 thus functions to center the large hole records and may be removed when small hole records are played. This central bore 92 of spool 91 is flared outwardly at each end in a manner similar to and for the same purpose as bore 22 of hub 21 (see Fig. 9).

Assume that a standard 78 R. P. M. turntable 15 is installed on the machine to which this device is to be attached, and assume further that the operator wishes to play first a 33½ R. P. M. and then a 45 R. P. M. record, in order to play the 33½ R. P. M. record the operator first places the device on the turntable 15, the spindle 17 of the turntable fitting into the bore 22 of hub 21 and the felt 32 on the lower side of plate 24 resting on the surface of the turntable 15 and causing the plate 24 and turntable at all times to rotate at same speed. The operator then places the record 19 over the spindle 17 so that it rests upon the felt 33 on the upper surface of plate 26 and hence plate 26 and record 19 at all times rotate at the same speed. The operator then depresses finger catch 82 of lower ring 35 which causes lower stop arm 62 to project under action of spring 64 so that ring 35 is held stationary by permanent projection 74 attached to the platform 16 of the machine. When the stop arm 62 projects and hence extension 83 moves out of the groove extension 84 in ring 35, the studs 87 move inwardly and are disengaged from the holes 88 in plates 24 and 25, thus permitting relative rotation of plate 24 and plate 25. The machine is then started. Rotation of the turn-

table 15 at 78 R. P. M. causes the ring gear 52 which is fixed to plate 24 to rotate at the same speed. Because of the gear ratio between ring gear 52, circular rack 48 and planetary gear 51, the center of said planetary gear 51 and hence plate 25 to which it is mounted rotate at a speed of 33½ R. P. M. Since the stop arm 62 of upper ring 36 is retracted and hence studs 87 affixed to said ring 36 are projected into holes 88 in plates 25 and 26, plate 26 rotates at 33½ R. P. M. Hence, record 19 rotates at such speed.

When it is desired to use a record having a 45 R. P. M. speed, the stop arm 62 of lower ring 35 is retracted by the operator, thus causing the studs 87 affixed to ring 35 to engage within holes 88 in plates 24 and 25, and thus causing the center plate 25 to rotate at the same speed as turntable 15. The operator depresses the finger catch 82 of upper ring 36 which allows the stop arm 62 to project under action of its spring 64 and engage the stationary projection 74 on platform 16. Thereupon, ring 36 is held stationary. The same action of projecting the stop arm 62 likewise permits the studs 87 of upper ring to disengage from holes 88 in plates 25 and 26 hence permit relative rotation of plates 25 and 26.

The operator then starts the machine which causes ring gear 53 to rotate at 78 R. P. M. Planetary gear portion 56 meshing with said ring gear 53 and fixed to planetary gear portion 57, which meshes with circular rack 49 of ring 36 causes the axis of planetary gear 54 and upper plate 26 to which it is pivotally connected to rotate at a speed of 45 R. P. M. which, therefore, causes the record 19 to rotate at such speed.

It will be understood that if a 78 R. P. M. record is to be played the operator may either remove the device from the turntable or leave the device on the turntable and retract both stop arms 62 in lower ring 35 and in upper ring 36. When both stop arms 62 are retracted studs 87 in lower ring 35 lock lower plate 24 and center plate 25 together, and studs 87 in upper ring 36 lock center plate 25 and upper plate 26 together. Thus, the record 19 rotates at the same speed as turntable 15—i. e., 78 R. P. M.

If it is desired to rotate the record at some other speed, such as approximately 25 R. P. M., both stop arms 62 are projected which causes both lower ring 35 and upper ring 36 to be held stationary and all of the studs 87 to be retracted so as to permit all three plates 24, 25 and 26 to revolve at different speeds. Ring gear 52 revolves at 78 R. P. M. and the axis of planetary gear 51 which meshes with both said ring gear 52 and stationary circular rack 48 rotates at 33½ R. P. M. which causes center plate 25 and ring gear 53 to rotate at 33½ R. P. M. Such speed of rotation of ring gear 53 results in a speed of rotation of upper plate 26 of approximately 25 R. P. M.

If through accident the operator installs the device upside down, no harm results because projection of the stop arms 62 does not result in the rings 35 and 36 being held stationary, for the curved surfaces 76 of the stop arms 62 do not engage the projections 74 on the platform 16 and the stop arms merely bypass such projections by momentarily retracting against the pressure of springs 64. Of course, projection of the stop arms 62 permits relative movement of the adjacent plates 24, 25 and 26 and hence the actual speed of the record 19 is indeterminant, being dependent upon the frictional resistance of the various relatively moving parts. The operator thus soon

becomes aware that the device has been installed upside down and rectifies the situation.

The device may be modified so as to convert turntables rotating at 33 1/3 R. P. M. or 45 R. P. M. to 78 R. P. M. This modification entails the installation of additional stop arms 94 which project in a direction opposite from arms 62 as shown in Fig. 10. It will be understood that in this modification the entire device is turned upside down so that the plate 26 engages the turntable 15 and the record 19 rests upon the plate 24 (i. e., opposite from normal use). Stop arms 93 are pivotally attached by pivots 94 to arms 62 and have curved surfaces 95 projecting in a direction opposite from surfaces 76. Said arms are biased outwardly by springs 96 which encompass pivots 94 and opposite ends of which bear against arms 62 and 93 respectively. The inner ends of arms 93 carry rollers 97 which travel within a recess 98 in cut out segment 61. Said rollers 97 nest in curved abutments 99 which limit movement of the rollers longitudinally of recess 98. Stop arms 93 on the rings 35 and 36 engage projection 74 on platform 16 and selectively either hold ring 35 or ring 36 stationary or lock or unlock the plates 24, 25 and 26 from rotation with each other. The gear ratio between the various intermeshing members thus results in a record speed of 78 R. P. M. for a turntable speed of either 33 1/3 R. P. M. or 45 R. P. M., the operator selecting the proper stop arm 92 for projection dependent upon the speed of the machine to which the device is attached.

It will also be seen that by proper use of this device a turntable speed of 45 R. P. M. may be converted to 33 1/3 R. P. M. or vice versa.

It will be apparent that this device may be used on phonographs having automatic record changing attachments as well as those playing records singly.

The invention has been described in rather complete detail by way of reference to example and illustration for purposes of clarity of understanding, but various changes and modifications in use, design and assembly may be practiced within the spirit of the invention and scope of the appended claims.

I claim:

1. A variable speed turntable comprising; a first apertured rotatable plate, a second apertured rotatable plate, a first ring gear fixedly mounted on said first rotatable plate, a second ring gear partially interposed between said plates and rotatable with respect to each said plate and arranged for rotation coaxially with respect to said plates, a planetary gear rotatably mounted on said second plate, said planetary gear meshing with both said ring gears, and means selectively operable by the operator for locking said first and second plates for rotation together, including an extensible arm carried by said second ring gear, and a pair of studs carried by said second ring gear, each of said studs being biased away from one of said plates, said arm being arranged when retracted to urge each said stud into an aperture in the respective plate toward which said stud is biased.

2. A variable speed turntable for use adjacent a stationary projection comprising; a first apertured, rotatable plate, a second apertured, rotatable plate, a first ring gear fixedly mounted on said first rotatable plate, a planetary gear rotatably mounted on said second rotatable plate, a second ring gear independent of said plates and partially interposed therebetween and arranged

for rotation coaxially with respect to said plates, said planetary gear meshing with both said ring gears, and means selectively operable by the operator for movement to two positions, one position holding said second ring gear stationary and the other position locking said first and second plates for rotation together, said means comprising an extensible arm carried by said second ring gear, movable to outward and inward positions and engageable when in outward position with said stationary projection, a pair of studs carried by said second ring gear, each of which is spring biased away from the respective plates which they face, and means on said arm arranged when said arm is in inward position to urge said studs toward and into engagement with apertures in the respective plates which they face.

3. A turntable as claimed in claim 2 which also includes latch means carried by said arm, cooperating latch means carried by said second ring gear, and means manually operable for disengaging said latch means from each other.

4. A variable speed turntable comprising, a first rotatable plate, a second rotatable plate, a third rotatable plate, a first ring gear independent of said plates and partially interposed between said first plate and said second plate, a second ring gear independent of said plates and partially interposed between said second plate and said third plate, a first sun gear fixedly mounted on said first rotatable plate, a first planetary gear rotatably mounted on said second rotatable plate and meshing with both said first sun gear and said first ring gear, a second sun gear mounted on said second rotatable plate, a second planetary gear meshing with both said second sun gear and said second ring gear and rotatably mounted on said third plate, and means selectively manually operable by the operator for holding said first ring gear and said second ring gear stationary.

5. A turntable as claimed in claim 4 for use adjacent a stationary abutment in which said means comprises extensible stop arms carried by each of said second ring gear and said first ring gear and selectively engageable with said stationary abutment.

6. A variable speed turntable comprising, a first rotatable plate, a second rotatable plate, a third rotatable plate, a first ring gear independent of said plates and partially interposed between said first plate and said second plate, a second ring gear independent of said plates and partially interposed between said second plate and said third plate, a first sun gear fixedly mounted on said first rotatable plate, a first planetary gear rotatably mounted on said second rotatable plate and meshing with both said first sun gear and said first ring gear, a second sun gear mounted on said second rotatable plate, a second planetary gear meshing with both said second sun gear and said second ring gear and rotatably mounted on said third plate, means selectively operable by the operator for locking said first plate and said second plate for rotation together, and means selectively operable for locking said second plate and said third plate for rotation together.

7. A turntable as claimed in claim 6 in which said plates are apertured and in which said means comprises extensible arms carried by each of said ring gears, and studs carried by each of said ring gears biased away from the plates which they face, said arms being arranged when retracted to urge said studs into apertures in adjacent plates.

8. A variable speed turntable comprising, a first rotatable plate, a second rotatable plate, a third

rotatable plate, a first ring gear independent of said plates and partially interposed between said first plate and said second plate, a second ring gear independent of said plates and partially interposed between said second plate and said third plate, a first sun gear fixedly mounted on said first rotatable plate, a first planetary gear rotatably mounted on said second rotatable plate and meshing with both said first sun gear and said first ring gear, a second sun gear mounted on said second rotatable plate, a second planetary gear meshing with both said second sun gear and said second ring gear and rotatably mounted on said third plate, first means selectively manually operable for movement to two positions, one position holding said first ring gear stationary and the other position locking said first and second plates for rotation together, and second means selectively manually operable for movement to two positions, one position holding said second ring gear stationary and the other position locking said second and third plates for rotation together.

9. A turntable as claimed in claim 8 and wherein is provided a stationary projection, in which said plates are apertured and in which each of said means comprises an extensible arm carried by its respective ring gear, movable to outward and inward positions and engageable when in outward position with said stationary projection, a pair of studs carried by said ring gears, each of which is spring biased away from the plates which they face, and means on each of said arms arranged when said arms are in inward position to urge said studs toward the plates which they face and into engagement with apertures in adjacent plates.

10. A variable speed turntable for use adjacent a stationary stud, said turntable comprising, a central interiorly bored hub, said hub being exteriorly threaded, a first plate, a second plate, a third plate, each of said plates fitting about and

being held concentric with respect to said hub, washers interposed between said plates adjacent said hub, means for securing said plates centrally disposed with respect to said hub and freely rotatable with respect to said hub and with respect to each other, a first ring gear surrounding and partially interposed between said first plate and said second plate, a second ring gear surrounding and partially interposed between said second plate and said third plate, rollers carried by each of said ring gears engaging adjacent plates and holding said plates parallelly disposed, a first sun gear fixed to said first plate, a first planetary gear rotatably mounted on said second plate and meshing with said first sun gear and said first ring gear, a second sun gear fixed to said second plate, a second planetary gear rotatably fixed to said third plate and meshing with said second sun and with said second ring gear, a first stop arm attached to and extensible from said first ring gear and engageable with said stationary stud to hold said first ring gear stationary and cause relative movement of said first plate with respect to said second plate, and means carried by said first ring gear and actuated upon retraction of said stop arm to lock said first plate and second plate for rotation together.
